UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

COAL-MINING MACHINE

Application filed December 2, 1924, Serial No. 753,495. Renewed July 26, 1930.

The present invention relates to certain new and useful improvements in coal mining machines, of the class whereby the coal is first undercut and, after the material above the undercut has been blasted down, is gathered from the floor of the mine and loaded into suitably positioned receptacles for transportation from the mine.

I am aware that machines have heretofore been proposed having conveyors adapted to receive material at the mine floor, and provided with mechanism adapted to form a kerf at the base of the vein, and after the material above said kerf has been broken down, to gather the disrupted and dislodged material from the mine floor and move it onto said conveyor. Machines such as above described, with which I am familiar, possess certain inherent defects which it is the object of this invention to overcome.

The especial object of this invention is to provide, in a machine of the class described, auxiliary gathering devices adapted to co-operate with the undercutting mechanism, after the coal has been shattered by the detonation of a suitably disposed explosive, to dislodge the disrupted coal and move it onto the conveyor.

A further object is to provide mechanism such as aforesaid, which may be conveniently shifted from its operative position adjacent the undercutting mechanism to an idle position remote therefrom to thereby avoid obstruction of the movement of the machine during the undercutting operation.

The means whereby I attain these objects are fully set forth in the following specification reference being had to the accompanying drawings of which—

Fig. 1 is a diagrammatic sectional view of a chamber in a coal mine including a general plan view of a machine embodying my present invention, arranged to undercut the coal preparatory to blasting it down.

Fig. 2 is a view similar to Fig. 1 illustrating the same machine arranged to gather the disrupted and dislodged coal from the mine floor and load it into a car suitably disposed upon the mine track in the rear of the machine.

Fig. 3 is a side elevation of the devices illustrated in Fig. 2.

Fig. 4 is a fragmentary plan view, on an enlarged scale, of the cutting and gathering devices shown as arranged in Fig. 2.

Fig. 5 is a side elevation of the devices illustrated in Fig. 4.

Fig. 6 is a fragmentary sectional view taken along the lines VI—VI of Fig. 4.

Fig. 7 is a fragmentary sectional view taken along the lines VII—VII of Fig. 4.

Fig. 8 is a transverse sectional view of the cutting and gathering devices taken along the line VIII—VIII of Fig. 4.

Fig. 9 is a fragmentary sectional view taken along the line IX—IX of Fig. 1.

Like numerals refer to similar parts in the several figures.

In Figs. 1, 2, and 3 of the drawings I have shown a coal mining machine such as is disclosed in my copending application Ser. No. 697,790, filed March 8, 1924, to which has been added dislodging and gathering mechanism which embodies all of the features of this invention. It is to be understood that they are but illustrative and not restrictive, and that they may be subject to wide variation as to details without departure from the spirit of my invention.

As shown in the drawings, the machine comprises a main supporting frame 1 which is adapted to rest upon and slide in any direction over the mine floor. Mounted upon the main frame 1 is a conveyor having a forward horizontal section 2 adapted to receive material at the mine floor, an inclined elevating section 3, and a horizontal delivery section 4. A similar conveyor 5 pivotally mounted upon the rear end of the supporting frame for swinging movement about a vertical axis, receives material from the conveyor section 3 and delivers it to suitably positioned receptacles in the rear of the machine such as the car 6, for transportation from the mine. A suitable motor 7 mounted upon the main frame 1 is connected by suitable gearing, not shown in the drawings, with the several elements of the machine to actuate them.

Projecting from the forward end of the

main frame 1, is a substantially horizontal elongated frame 8 along the lateral edges of which are formed guideways wherein travels an endless chain 9 of the well known type having sockets formed upon its links wherein are fixed renewable cutter bits 10 adapted to engage the coal to cut it. Feeding mechanism is provided which comprises the feed ropes 11 and 12 adapted to be attached to suitably positioned abutments external of the machine, such as the anchor jacks 13 and 14, and which are windable upon suitable winding drums mounted upon the machine frame. These winding drums are provided with controlling devices whereby the winding and unwinding of the ropes may be controlled for moving and guiding the machine in any preferred direction over the mine floor. As all of the devices above referred to are well understood in the mining machine art, and as they form no part in the present invention, and are fully disclosed in my copending application above referred to, their illustration and description is not thought to be required at this time.

Journaled in suitable bearings 15 and 16, formed in the forward part of the main frame 1, is a vertical shaft 17 to which is fixed a bevel gear 18. The gear 18 engages a suitable bevel pinion 19 fixed to the forward end of a longitudinally extending power shaft 20 which is connected by suitable gearing not shown in the drawings, with the motor 7. A sprocket wheel 21 fixed to the lower end of the vertical shaft 20 engages the cutter chain 9 to actuate it. The trough of the conveyor section 2 terminates forwardly in a flat plate 22 positioned in contact with the mine floor and extending beneath the sprocket wheels 21. When the cutter chain 9 is actuated the cutter bits 10 will drag the coal cuttings, and any other loose material coming within their path, onto the plate 22 and within the path of the conveyor flights 23 to be conveyed thereby rearwardly of the machine.

In the method of mining here contemplated the coal is dislodged and removed in successive increments, producing a step by step advance of the working face. The cycles of operation consist of first forming a kerf, preferably, and as here shown at the base of the vein, then disrupting the coal above the kerf by any suitable means, such as by blasting, and afterwards gathering the dislodged coal from the floor of the mine and transferring it to suitably positioned receptacles for transportation from the mine.

Preparatory to the formation of the underkerf, the machine above described is positioned upon the mine floor at one side of the mine chamber, as here shown the right hand side, since the cutter chain has, in the present showing, a direction of travel which necessitates working from the right to the left. It will be understood, of course, that with the

kerf forming mechanism traveling in an opposite direction, movement would be from left to right. The forward end of the cutter bar 8 projects into the angle formed by the face 24 with the rib 25. The feed rope 11 is drawn out from its winding drum, passed around the guide sheaves 26 and 27 at the forward end of the main frame, and attached to a suitable anchor jack 13 positioned at the left hand side of the mine chamber adjacent the working face 24. The feed rope 12 is then drawn out from its winding drum, passed around the guide sheave 28 at the rearward end of the main frame, and attached to a suitable anchor jack 14 positioned adjacent the right hand rib 25 in advance of the guide sheave 28. When the cutter chain is actuated and the mechanism which controls the winding drums is suitably manipulated the feed rope 11 will be held against unwinding, and the feed rope 12 will be wound upon its drum, moving the machine bodily longitudinally forward, swinging on the feed rope 11 about the anchor jack 13 to cause the cutter arm 8 to be thrust longitudinally into the coal to form the sumping or entering cut. After the cutter arm 8 has entered the coal to a sufficient depth, the feed mechanism upon the machine will be again manipulated to cause the winding of the feed rope 11 to draw the machine bodily laterally causing the cutter arm 8 to cut a kerf across the face of the chamber, the feed rope 12 meanwhile being permitted to unwind under frictionally controlled resistance to maintain the desired angular relation between the longitudinal lines of the cutter arm and the working face. When the cutter arm 8 has advanced to the line of the left hand rib 29 the anchor jacks 13 and 14 will be repositioned so that tension upon the ropes 11 and 12 will withdraw the machine from the coal in the manner which is well understood by those skilled in the use of shortwall mining machines.

Holes may then be drilled in the coal above the underkerf, and these holes loaded with suitable explosives by the detonation of which the coal is broken down. When insufficiently shattered by the blast the fragments of coal remain so interlocked that the cutter chain forms a new kerf beneath the mass of partly broken coal without dragging the overhanging fragments onto the conveyor. The excessive use of explosives, however, so shatters the coal as to materially reduce its value, and a happy medium is desirable which cannot always be attained in practice. To facilitate dislodging and gathering the broken coal without excessive blasting I have provided the auxiliary dislodging and gathering devices hereinafter described which are adapted to cooperate with the cutting devices during the loading operation.

Pivotedly mounted upon the main frame 1 for rotation about the axis of the vertical

shaft 17, is a yoke 30 to which is fixed a horizontally projecting elongated frame 31 having guideways along its lateral edges wherein travels a cutter chain 32 similar to the chain 9. The frame 31 is bent laterally at 33, as shown in Fig. 4 of the drawings, for a purpose which will hereinafter be more fully explained. The cutter chain 32 engages a sprocket wheel 34 mounted for free rotation upon the vertical shaft 17, and a clutch member 35 having clutch teeth 36 adapted to engage suitable apertures in the hub 37 of the sprocket wheel 34, is splined to the shaft 17 and is adapted to operatively connect the sprocket wheel 34 with the shaft 17. A shifting lever 38 pivoted at 39 upon the yoke 30 is adapted to move the clutch member 35 into and out of engagement with the sprocket wheel 34 and means is provided for locking the shifting lever 38 in either of its positions by a cotter pin 40 adapted to be thrust through a suitable aperture in an upstanding flange 41 of the yoke 30.

At the outer end of the guide frame 31 is formed a downwardly projecting journal bearing 42 in which is rotatably mounted a vertical shaft 43. To the upper end of the shaft 43 is fixed a sprocket wheel 44 which engages and is actuated by the cutter chain 32. To the lower end of the shaft 43 is fixed a similar sprocket wheel 45 which engages and actuates an endless cutter chain 46 similar to the chains 9 and 32. The chain 46 is supported in guideways formed along the lateral edges of an auxiliary guide frame 47 which is rigidly attached to the under side of the guide frame 31 in any suitable manner, as by brackets 47.

During the loading operation the auxiliary guide frames 31 and 47 occupy a position extending forwardly from the main frame substantially parallel with and directly above the cutter frame 8 to which they are rigidly attached by a removable coupling bar 48. The coupling bar 48 is formed of a steel bar of suitable cross section adapted to project between a pair of downwardly extending flanges 49 attached to the guide frame 47, and to be locked in that position by a coupling pin 50 thrust through suitable apertures in the flanges 49 and coupling bar 48. To the lower end of the coupling bar 48 is attached a downwardly projecting stud 51 having a cross head 52 adapted to be thrust through a suitably formed aperture in the top plate 53 of the cutter frame 8, and to be turned cross-ways thereof so as to engage the underside of said plate and lock the bar 48 securely thereto. When the parts are thus arranged the three cutter chains 9, 32, and 46 may be simultaneously brought into effective contact with the mass of dislodged coal to tear out the interlocked fragments and move them towards and onto the plates 22 of the conveyor.

It is apparent that the gathering devices above described, if left in their operative position during the under cutting operation, would tend to cut additional kerfs extending over substantially the entire height of the vein, thereby producing excessive amounts of slack and entirely destroying the commercial value of the coal. These auxiliary devices are, therefore, adapted to be removed to a position remote from the coal face when not required for the specific service for which they are designed. After all of the dislodged coal has been loaded out, and preparatory to the next step in the advance of the coal face the clutch 35 will be disengaged from the sprocket wheel 34 to allow the chains 32 and 46 to remain idle, after which the guide bars 31 and 47 will be moved to their inoperative position. The coupling pin 50 will be withdrawn to release the upper end of the coupling bar 48 from the flanges 49 of the guide frame 47, the bar 48 rotated about the stud 51 to release the cross head 52 and thereby disconnect said coupling bar from the guide frame 8. The guide frames 31 and 47 will then be swung about their pivotal support into the position illustrated in Fig. 1 of the drawings, where by virtue of the bend 33 in the frame 30 they lie closely adjacent and substantially parallel to the side of the machine where they will not impede its freedom of movement during the cutting operation. A bar 56 projecting from the main frame 1 near the vertical shaft 17 as illustrated in Figs. 1 and 9, is adapted to engage the shifting lever 38 when the auxiliary frame 31 is in its idle position, to insure the disengagement of the clutch member 35, prevent any accidental clutch engagement and preclude possible injury to the operator by accidental contact with the moving chain 32 during the undercutting operation.

A removable scraper apron 54 having attachment bars 55 adapted to extend into suitable apertures of the plate 53 of the cutter frame is provided along the rear of cutter frame 8 to engage fragments of coal falling in the rear of the cutter frame 8 and hold them in the path of the cutter chain 9 to insure their removal from the floor of the mine.

What I claim is:

1. In a coal mining machine, the combination with a main supporting frame adapted to rest upon and slide in any direction over the mine floor, means to move and guide said frame relative to the material to be mined, a conveyor mounted upon said frame, an elongated cutter arm carried by said main frame projecting therefrom in fixed relation with said conveyor, a cutter chain carried by said cutter arm adapted to cut a path therefor in immovable masses of material and to move loose material onto said conveyor, an auxiliary cutter arm pivotally mounted upon said main frame and adapted

to be held in fixed relation with the first mentioned cutter arm, and a cutter chain carried by said auxiliary cutter arm and adapted to cooperate with the first mentioned cutter chain to dislodge disrupted material and move it onto said conveyor.

2. In a coal mining machine, the combination with a main supporting frame adapted to rest upon and slide in any direction over the mine floor, means to move and guide said frame relative to the material to be mined, a conveyor mounted upon said frame, an elongated cutter arm carried by said main frame projecting therefrom in fixed relation with said conveyor, a cutter chain carried by said cutter arm adapted to cut a path therefor in immovable masses of material and to move loose material onto said conveyor, a plurality of auxiliary cutter arms pivotally mounted upon said main frame and adapted to be held in fixed relation with the first mentioned cutter arm, and a cutter chain carried by each of said auxiliary cutter arms adapted to cooperate with the first mentioned cutter chain to dislodge disrupted material and move it onto said conveyor.

3. In a coal mining machine, the combination with a conveyor adapted to receive material at the floor of the mine, an elongated cutter arm projecting horizontally in fixed relation with said conveyor and movable therewith relative to the material to be mined, an endless cutter chain adapted to travel in guideways of said cutter arm and to cut a path therefor in immovable masses of material and to move loose material onto said conveyor, and an auxiliary cutter arm adapted to be positioned adjacent the first mentioned cutter arm and held in fixed relation therewith or to be removed to a position remote therefrom, and an auxiliary cutter chain carried by said auxiliary cutter arm adapted to cooperate with the first mentioned chain when positioned adjacent thereto to dislodge disrupted material and move it onto said conveyor.

4. In a coal mining machine, the combination with a main supporting frame adapted to rest upon and slide in any direction over the mine floor, means to move and guide said frame relative to the material to be mined, a conveyor mounted upon said frame, an elongated cutter arm carried by said main frame projecting therefrom in fixed relation with said conveyor, a cutter chain carried by said cutter arm adapted to cut a path therefor in immovable masses of material and to move loose material onto said conveyor, an auxiliary cutter arm pivotally mounted upon said main frame above the first mentioned cutter arm and adapted to swing about a vertical axis or to be held in fixed relation with the first mentioned cutter arm, and an auxiliary cutter chain carried by said auxiliary cutter arm adapted to cooperate with the first men-

tioned cutter chain to dislodge disrupted material and move it onto said conveyor.

5. In a coal mining machine, the combination with a main supporting frame adapted to rest upon and slide in any direction over the mine floor, means to move and guide said frame relative to the material to be mined, a conveyor mounted upon said frame, an elongated cutter arm carried by said main frame projecting therefrom in fixed relation with said conveyor, a cutter chain carried by said cutter arm adapted to cut a path therefor in immovable masses of material and to move loose material onto said conveyor, an auxiliary cutter arm mounted upon said main frame and adapted to be held in fixed relation adjacent the first mentioned cutter arm or to be moved to a position remote therefrom, and an auxiliary cutter chain carried by said auxiliary cutter arm adapted to cooperate with the first mentioned cutter chain when in position adjacent thereto to dislodge disrupted material and move it onto said conveyor.

6. In a coal mining machine, the combination with a conveyor adapted to receive material adjacent the coal face and to transport it rearwardly of the machine, an elongated frame pivotally mounted adjacent the receiving end of said conveyor, an endless chain adapted to travel in guideways formed upon the lateral edges of said frame, material engaging elements attached to said chain adapted to engage and dislodge disrupted material and move it towards said conveyor, a secondary guide-frame carried by the first mentioned guide frame, an endless chain adapted to travel in guideways formed on the lateral edges of said secondary guide frame and having material engaging elements adapted to cooperate with the first mentioned elements to dislodge disrupted material and move it towards said conveyor, and means actuated by the first mentioned chain to actuate the second mentioned chain as and for the purpose set forth.

7. In a coal mining machine, the combination with a conveyor adapted to receive material adjacent the coal face and transport it rearwardly of the machine, an elongated frame pivotally mounted adjacent the receiving end of the conveyor, an endless chain adapted to travel in guideways formed upon the lateral edges of said frame, material engaging elements attached to said chain adapted to engage and dislodge disrupted material and move it towards said conveyor, a secondary guide frame rigidly supported beneath said first mentioned guide frame, an endless chain adapted to travel in guideways formed along the lateral edges of said secondary guide frame and having material engaging elements adapted to cooperate with the first mentioned elements to dislodge disrupted material and move it towards said

conveyor, and means actuated by the first mentioned chain to actuate the second mentioned chain as and for the purpose set forth.

8. In a coal mining machine, the combination with a conveyor adapted to receive material adjacent the coal face and to transport it rearwardly of the machine, an elongated frame pivotally mounted adjacent the receiving end of said conveyor, an endless chain adapted to travel in guideways formed upon the lateral edges of said frame, material engaging elements attached to said chain adapted to engage and dislodge disrupted material to move it towards said conveyor, a secondary guide frame attached to said first mentioned guide frame, an endless chain adapted to travel in guideways formed along the lateral edges of said secondary guide frame and having material engaging elements adapted to co-20 operate with the first mentioned elements to dislodge disrupted material and move it towards said conveyor, a vertical shaft mounted adjacent the outer end of said guide frames and having sprocket wheels adapted to engage said endless chains to operatively connect them together.

9. In a coal mining machine, a supporting frame, and cutting mechanism carried thereby comprising an endless chain, cutter bits 30 carried by said chain, an elongated relatively narrow guide frame having substantially parallel guideways formed in its lateral edges along which said chain is adapted to travel to cause said cutter bits to engage the material to be mined, said guide frame being pivotally mounted to swing about a vertical axis laterally remote from the extended longitudinal central lines of the effective part of said cutting mechanism.

40 10. In a coal mining machine, the combination with an elongated main supporting frame, of an elongated guide frame pivotally mounted at the forward end thereof and adapted to swing about a vertical axis positioned within said supporting frame from an active position projecting forwardly thereof to an idle position extending rearwardly of said pivotal support, said guide frame being bent laterally adjacent its pivotal support to cause its idle position to lie outside of said supporting frame parallel to the longitudinal lines thereof, and an endless cutter chain adapted to travel in guideways of said guide frame.

55 11. In a coal mining machine, the combination with a main supporting frame, of an elongated guide frame pivotally mounted upon said main frame and adapted to swing about a vertical axis in the central longitudinal vertical plane of said main frame from an active position projecting forwardly thereof to an idle position extending rearwardly of said axis, said guide frame being bent laterally adjacent its pivotal support to

cause its idle position to lie outside of but parallel with said main frame.

12. In a coal mining machine, the combination with an elongated main supporting frame, an endless cutter chain adapted to travel in horizontal planes to engage the material to be mined, and an elongated guide frame for said chain pivotally supported for swinging movement about a vertical axis in the longitudinal central vertical plane of said supporting frame, and bent laterally adjacent its pivotal support to cause the effective part of said chain to travel along lines parallel with but laterally remote from said central vertical plane.

70 13. In a coal mining machine, the combination with an elongated main supporting frame, of an endless cutter chain adapted to travel along straight lines to engage the material to be mined, and an elongated guide frame for said chain pivotally supported for swinging movement about a vertical axis in the longitudinal central vertical planes of said supporting frame and bent laterally adjacent its pivotal support to cause the effective part of said chain to travel along straight lines parallel with but laterally remote from said central vertical plane.

75 14. In a coal mining machine, the combination with an elongated main supporting frame adapted to be moved relative to the material to be mined, an elongated kerf cutter rigidly attached to and projecting in longitudinal alignment with said main frame and adapted to form a kerf at the base of the vein, a supplemental elongated cutting mechanism pivotally mounted upon the main frame for swinging movement about a vertical axis in the central longitudinal vertical plane thereof and so shaped that its effective part may project forwardly of said main frame along lines parallel with but laterally removed from said central vertical plane at one side thereof or may project rearwardly of its pivotal support along lines parallel with but laterally removed from said longitudinal central plane at the other side thereof.

80 15. In a coal mining machine, the combination with an elongated main supporting frame adapted to be moved relative to the material to be mined, an elongated kerf cutter rigidly attached to and projecting in longitudinal alignment with said main frame and adapted to form a kerf at the base of the vein, a supplemental elongated cutting mechanism pivotally mounted upon the main frame for swinging movement about a vertical axis in the central longitudinal vertical plane thereof and adapted to project forwardly of said main frame along lines parallel with but laterally removed from said central vertical plane at one side thereof or to project rearwardly of its pivotal

support along lines parallel with but laterally removed from said central vertical plane at the other side thereof.

16. In a machine of the class described, the combination of conveying mechanism, cutting mechanism to form a single kerf in a coal face and adapted also to gather loose material and deliver it to said conveying mechanism, and gathering mechanism adjacent said cutting mechanism and movable relative thereto into position to cooperate therewith in a plane spaced therefrom to engage and deliver loose material to said conveying mechanism.

17. In a machine of the class described, the combination of conveying mechanism, cutting mechanism projecting forwardly of said conveying mechanism to form a kerf in a coal face at the mine floor and adapted also to gather loose material and deliver it to said conveying mechanism, and gathering mechanism above said cutting mechanism and cooperable therewith to engage and deliver loose material to said conveying mechanism.

18. In a machine of the class described, the combination of conveying mechanism, cutting mechanism projecting forwardly from said conveying mechanism and in fixed relation thereto to form a kerf in a coal face and adapted also to gather loose material and deliver it to said conveying mechanism, and gathering mechanism adjacent said cutting mechanism and swingable relative thereto into position to cooperate therewith to engage and deliver loose material to said conveying mechanism.

19. In a machine of the class described, the combination of conveying mechanism, cutting mechanism projecting forwardly from said conveying mechanism and in fixed relation thereto to form a kerf in a coal face and adapted also to gather loose material and deliver it to said conveying mechanism, and gathering mechanism adjacent said cutting mechanism and movable into cooperating position therewith to engage and deliver loose material to said conveying mechanism.

20. In a machine of the class described, the combination of conveying mechanism, cutting mechanism projecting forwardly from said conveying mechanism and in fixed relation thereto to form a single kerf in a coal face and adapted also to gather loose material and deliver it to said conveying mechanism, and a plurality of gathering mechanisms lying in different planes relative to said cutting mechanism and movable into position to cooperate therewith to engage and deliver loose material to said conveying mechanism.

21. In a machine of the class described, the combination of conveying mechanism, cutting mechanism projecting forwardly from said conveying mechanism and in fixed

relation thereto to form a single kerf in a coal face and adapted also to gather loose material and deliver it to said conveying mechanism, and a plurality of gathering mechanisms lying in different planes above said cutting mechanism and movable into position to cooperate therewith to engage and deliver loose material to said conveying mechanism.

22. In a machine of the class described, the combination of conveying mechanism, cutting mechanism projecting forwardly from said conveying mechanism and in fixed relation thereto to form a kerf in a coal face and adapted also to gather loose material and deliver it to said conveying mechanism, and a plurality of gathering mechanisms adjacent said cutting mechanism and movable into cooperating position therewith to engage and deliver loose material to said conveying mechanism.

23. In a machine of the class described, the combination of conveying mechanism, cutting mechanism projecting forwardly from said conveying mechanism and in fixed relation thereto to form a kerf in a coal face and adapted also to gather loose material and deliver it to said conveying mechanism, and a plurality of pivotally mounted gathering mechanisms adjacent said cutting mechanism and movable into cooperating position therewith to engage and deliver loose material to said conveying mechanism.

24. In a machine of the class described, the combination of conveying mechanism, cutting mechanism to form a kerf in a coal face adapted to gather loose material and deliver it to said conveying mechanism, gathering mechanism adjacent said cutting mechanism and cooperating therewith to engage and deliver loose material to said conveying mechanism, said gathering mechanism being movable from an active position adjacent said cutting mechanism to an inactive position in rear of said cutting mechanism, means for locking said gathering mechanism in active position, and means for locking said gathering mechanism in inactive position.

25. In a machine of the class described, the combination of conveying mechanism, cutting mechanism to form a kerf in a coal face adapted to gather loose material and deliver it to said conveying mechanism, pivotally mounted gathering mechanism adjacent said cutting mechanism and cooperating therewith to engage and deliver loose material to said conveying mechanism, said gathering mechanism being movable from an active position adjacent said cutting mechanism to an inactive position in rear of said cutting mechanism, means for locking said gathering mechanism in active position, and means for locking said gathering mechanism in inactive position.

26. In a machine of the class described, the

combination of conveying mechanism, cutting mechanism to form a kerf in a coal face adapted to gather loose material and deliver it to said conveying mechanism, a plurality of pivotally mounted gathering mechanism lying in different planes above said cutting mechanism and cooperating therewith to engage and deliver loose material to said conveying mechanism, said gathering mechanism being movable from an active position adjacent said cutting mechanism to an inactive position in rear of said cutting mechanism, means for locking said gathering mechanism in active position, and means for locking said gathering mechanism in inactive position.

27. In a machine of the class described, the combination of conveying mechanism, cutting mechanism to form a kerf in a coal face and adapted to gather loose material and deliver it to said conveying mechanism, gathering mechanism cooperating with said cutting mechanism to engage and deliver loose material to said conveying mechanism, said gathering mechanism being movable from an active position adjacent said cutting mechanism to an inactive position in rear thereof, means to lock said gathering mechanism in active position, means to lock said gathering mechanism in inactive position, and means automatically to prevent unlocking of said gathering mechanism when in inactive position.

28. In a machine of the class described, the combination of conveying mechanism, cutting mechanism to form a kerf in a coal face and adapted to gather loose material and deliver it to said conveying mechanism, gathering mechanism cooperating with said cutting mechanism to engage and deliver loose material to said conveying mechanism, said gathering mechanism being movable from an active position adjacent said cutting mechanism to an inactive position in rear thereof, means to lock said gathering mechanism in active position, means to lock said gathering mechanism in inactive position, and means engaging said last named locking means upon movement of said gathering devices to inactive position automatically to prevent unlocking of said gathering means when in inactive position.

29. In a machine of the class described, the combination of conveying mechanism, cutting mechanism to form a kerf in a coal face and adapted also to gather loose material and deliver it to said conveying mechanism, a plurality of gatherers lying in planes above the plane of said cutting mechanism, said gatherers being movable from an active position of said cutting mechanism to inactive positions in the rear thereof, means for driving said cutting mechanism and gatherers, means for intermitting the drive of said gatherers, and means automatically to lock the gatherer

driving mechanism when said gatherers are in inactive position.

30. In a machine of the class described, the combination of conveying mechanism, cutting mechanism to form a kerf in a coal face and adapted also to gather loose material and deliver it to said conveying mechanism, a plurality of gatherers lying in planes above the plane of said cutting mechanism, said gatherers being movable from an active position of said cutting mechanism to inactive positions in the rear thereof, a common driving means for driving said cutting mechanism and gatherers, means for intermitting the drive of said gatherers, and means automatically to lock the gatherer driving mechanism when said gatherers are in inactive position.

31. In a machine of the class described, the combination of conveying mechanism, cutting mechanism to form a kerf in a coal face and adapted also to gather loose material and deliver it to said conveying mechanism, gathering mechanism adjacent said cutting mechanism and cooperating therewith to engage and deliver loose material to said conveying mechanism, said gathering mechanism being movable from an active position relative to said cutting mechanism to an inactive position in rear thereof, a common drive shaft for said cutting mechanism and said gathering mechanism, means for connecting and disconnecting said shaft, and means to prevent operation of said shaft and coupling mechanism when said gathering mechanism is in inactive position.

32. In a machine of the class described, the combination of conveying mechanism, cutting mechanism to form a kerf in a coal face and adapted also to gather loose material and deliver it to said conveying mechanism, gathering mechanism adjacent said cutting mechanism and cooperating therewith to engage and deliver loose material to said conveying mechanism, said gathering mechanism being movable from an active position relative to said cutting mechanism to an inactive position in rear thereof, a common drive shaft for said cutting mechanism and said gathering mechanism, means for connecting and disconnecting said gathering mechanism from said shaft, and means automatically to render said shaft coupling mechanism unoperable when said gathering mechanism has moved to its inactive position.

33. In a machine of the class described, the combination of conveying mechanism, cutting mechanism to form a kerf in a coal face and adapted also to gather loose material and deliver it to said conveying mechanism, a driving shaft for said cutting mechanism, gathering mechanism pivotally mounted on said shaft and offset laterally therefrom, said gathering mechanism being movable from an active position adjacent said cutting mechanism to an inactive position in rear thereof

above-said conveying mechanism and substantially within the boundaries of said conveying mechanism, means for coupling said gathering mechanism to said shaft for driving, and means automatically to prevent driving connection between said gathering mechanism and said shaft when said gathering mechanism is in inactive position.

34. In a machine of the class described, the combination of conveying mechanism, cutting mechanism to form a kerf in a coal face and adapted also to gather loose material and deliver it to said conveying mechanism, gathering mechanism adjacent said cutting mechanism and cooperating therewith to engage and deliver loose material to said conveying mechanism, and means at one side of and directly behind said cutting and gathering mechanisms to prevent the escape of loose material.

35. In a machine of the class described, the combination of conveying mechanism, cutting mechanism to form a kerf in a coal face and adapted also to gather loose material and deliver it to said conveying mechanism, gathering mechanism adjacent said cutting mechanism and cooperating therewith to engage and deliver loose material to said conveying mechanism, and removable means at one side of and directly behind said cutting and gathering mechanisms to prevent the escape of loose material.

36. In a machine of the class described, the combination of conveying mechanism, cutting mechanism to form a kerf in a coal face and adapted also to gather loose material and deliver it to said conveying mechanism, gathering mechanism adjacent said cutting mechanism and cooperating therewith to engage and deliver loose material to said conveying mechanism, and a substantially vertically disposed apron at one side of and directly behind said cutting and gathering mechanisms to prevent the escape of loose material.

37. In a machine of the class described, the combination of conveying mechanism, cutting mechanism to form a kerf in a coal face and adapted also to gather loose material and deliver it to said conveying mechanism, gathering mechanism adjacent said cutting mechanism and cooperating therewith to engage and deliver loose material to said conveying mechanism, and an apron having substantially vertical and horizontal walls at one side of said cutting and gathering mechanism to prevent the escape of loose material.

38. In a machine of the class described, the combination of conveying mechanism, a plurality of gathering mechanisms lying in different horizontal planes adapted to gather loose material and deliver it to said conveying mechanisms, means for driving said gathering mechanisms, and means for coupling one or more of said gathering mechanisms and said driving means.

39. In a machine of the class described, the combination of conveying mechanisms, a plurality of gathering mechanisms, one at least of which is fixed relative to said conveying mechanism, and one at least of which is movable from an active to an inactive position relative to said fixed gatherer and said conveying mechanism and in a plane spaced from that of said fixed gatherer, common driving means for said gatherers, and means for coupling and uncoupling said movable gatherers with respect to said common driving means.

40. In a machine of the class described, the combination of conveying mechanisms, a plurality of gathering mechanisms, one at least of which is fixed relative to said conveying mechanism, and one at least of which is movable from an active to an inactive position relative to said fixed gatherer and said conveying mechanism and in a plane spaced from that of said fixed gatherer, common driving means for said gatherers, means for coupling and uncoupling said movable gatherers with respect to said common driving means, and means to prevent operation of the driving connection between said movable gatherers and said driving means.

41. In a machine of the class described, the combination of conveying mechanisms, a plurality of gathering mechanisms, one at least of which is fixed relative to said conveying mechanism, and one at least of which is movable from an active to an inactive position relative to said fixed gatherer and said conveying mechanism, common driving means for said gatherers, means for coupling and uncoupling said movable gatherers with respect to said common driving means, and means automatically to prevent operation of the driving connection between said movable gatherers and said driving means when said movable gatherers are moved to inactive position.

42. In a machine of the class described, the combination of conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, and gathering mechanism extending forward from said conveyor mechanism and lying in a plane above said cutting mechanism to gather loose material and deliver it to said conveying mechanism, said gathering mechanism being movable from an active position adjacent the cutting mechanism to an inactive position in rear of said cutting mechanism and in a plane above said conveying mechanism.

43. In a machine of the class described, the combination of conveying mechanism com-

prising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, and a plurality of gathering mechanisms extending forward from said conveyor mechanism and lying in planes above said cutting mechanism to gather loose material and deliver it to said conveying mechanism, said gathering mechanisms being movable from active positions adjacent the cutting mechanism to inactive positions in rear of said cutting mechanism, and in a plane above said conveying mechanism.

44. In a machine of the class described, the combination of conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, and a plurality of gathering mechanisms extending forward from said conveyor mechanism and lying in planes above said cutting mechanism to gather loose material and deliver it to said conveying mechanism, said gathering mechanisms being connected and movable together from active positions adjacent cutting mechanism.

45. In a machine of the class described, the combination of conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, gathering mechanism extending forward from said conveyor mechanism and lying in a plane above said cutting mechanism to gather loose material and deliver it to said conveying mechanism, a second gathering mechanism carried by said first named gathering mechanism to gather loose material and deliver it to said conveying mechanism, said gathering mechanisms being movable from active positions adjacent the cutting mechanism to inactive positions in rear of said cutting mechanism and in a plane above said conveying mechanism.

46. In a machine of the class described, the combination of conveying mechanism comprising a conveyor pan having an open receiving end adapted to lie upon a mine floor and receive loose material therefrom, cutting mechanism extending forwardly of said pan

and lying in substantially the plane of the conveyor adapted to form a kerf in the coal face and also to gather loose material and deliver it to said conveyor, gathering mechanism extending forward from said conveyor mechanism and lying in a plane above said cutting mechanism to gather loose material and deliver it to said conveying mechanism, a second gathering mechanism suspended from said first named gathering mechanism to gather loose material and deliver it to said conveying mechanism, said gathering mechanisms being movable from active positions adjacent the cutting mechanism to inactive positions in rear of said cutting mechanism and in a plane above said conveying mechanism.

47. In a machine of the class described, the combination of conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, gathering mechanism extending forward from said conveyor mechanism and lying in a plane above said cutting mechanism to gather loose material and deliver it to said conveying mechanism, a second gathering mechanism suspended and offset from said first named gathering mechanism to gather loose material and deliver it to said conveying mechanism, said gathering mechanisms being movable from active positions adjacent the cutting mechanism to inactive positions in rear of said cutting mechanism and in a plane above said conveying mechanism.

48. In a machine of the class described, the combination of conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, gathering mechanism extending forward from said conveyor mechanism and lying in a plane above said cutting mechanism to gather loose material and deliver it to said conveying mechanism, a common driving shaft for said cutting mechanism and said gathering mechanism, means for coupling and uncoupling said gathering mechanism from said shaft, a second gathering mechanism lying between said cutting mechanism and said first named gathering mechanism, and driving connections between said first gathering mechanism and said second gathering mechanism.

49. In a machine of the class described, the combination of conveying mechanism

comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, gathering mechanism extending forward from said conveyor mechanism and lying in a plane above and laterally offset from said cutting mechanism, means for driving said cutting and gathering mechanism, a second gathering mechanism interposed between said cutting mechanism and said first named gathering mechanism, and laterally offset therefrom, and means for driving said second gathering mechanism, said gathering mechanisms being movable from active positions adjacent the cutting mechanism to inactive positions in rear of said cutting mechanism and in a plane above said conveying mechanism.

50. In a machine of the class described, the combination of conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, gathering mechanism extending forward from said conveyor mechanism in a plane above said cutting mechanism to gather loose material and deliver it to said conveying mechanism, a second gathering mechanism rigidly supported by said first named gathering mechanism in a plane between said first gathering mechanism and said cutting mechanism, means for driving said cutting mechanism and said first gathering mechanism, and driving connections between said first gathering mechanism and said second gathering mechanism, said gathering mechanisms being movable from active positions adjacent the cutting mechanism to an inactive position in rear of said cutting mechanism and in planes above said conveying mechanism.

51. In a machine of the class described, the combination of conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, gathering mechanism extending forward from said conveyor mechanism in a plane above said cutting mechanism to gather loose material and deliver it to said conveying mechanism, a second gathering mechanism rigidly sup-

ported by said first named gathering mechanism in a plane between said first gathering mechanism and said cutting mechanism, means for driving said cutting mechanism and said first gathering mechanism, and driving connections between said first gathering mechanism and said second gathering mechanism, and means for locking the gathering mechanisms to the cutting mechanism when in active position, said gathering mechanisms being movable from active positions adjacent the cutting mechanism to an inactive position in rear of said cutting mechanism, and in planes above said conveying mechanism. 70 75 80

52. In a machine of the class described, the combination of conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, gathering mechanism extending forward from said conveyor mechanism in a plane above said cutting mechanism to gather loose material and deliver it to said conveying mechanism, a second gathering mechanism rigidly supported by said first named gathering mechanism in a plane between said first gathering mechanism and said cutting mechanism, means for driving said cutting mechanism and said first gathering mechanism, and driving connections between said first gathering mechanism and said second gathering mechanism, and removable means to lock said gathering mechanisms to the cutting mechanism when in active position, said gathering mechanisms being movable from active positions adjacent the cutting mechanism to an inactive position in rear of said cutting mechanism and in planes above said conveying mechanism. 105

53. In a machine of the class described, the combination of a conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and deliver it to said conveyor, gathering mechanism extending forward from said conveyor mechanism in a plane above said cutting mechanism to gather loose material and deliver it to said conveying mechanism, a second gathering mechanism rigidly supported by said first named gathering mechanism in a plane between said first gathering mechanism and said cutting mechanism, means for driving said cutting mechanism and said first gathering mechanism, and driving con-

nections between said first gathering mechanism and said second gathering mechanism, a locking bar removably mounted on said cutting mechanism to lock said cutting and gathering mechanisms in active positions, said gathering mechanisms being movable from active positions adjacent the cutting mechanism to an inactive position in rear of said cutting mechanism, and in planes above said 10 conveying mechanism.

54. In a machine of the class described the combination of conveying mechanism comprising a conveyor pan having an open receiving end adapted to lie upon a mine floor and receive loose material therefrom, cutting mechanism extending forwardly of said pan and lying in substantially the plane of the conveyor adapted to form a kerf in the coal face and also to gather loose material and 15 deliver it to said conveyor, gathering mechanism extending forward from said conveyor mechanism in a plane above said conveying mechanism to gather loose material and deliver it to said conveying mechanism, a second gathering mechanism rigidly supported by said first named gathering mechanism in a plane between said first gathering mechanism and said cutting mechanism, means for driving said cutting mechanism and said first 20 gathering mechanism, and driving connections between said first gathering mechanism and said second gathering mechanism, a transversely disposed locking bar removably mounted on said cutting mechanism to lock 25 said cutting mechanism and said gathering mechanisms in active position, said gathering mechanisms being movable from active positions adjacent the cutting mechanism to an inactive position in rear of said cutting 30 mechanism, and in planes above said conveying mechanism.

55. In a machine of the class described, a frame, a gathering device fixed thereto, a second gathering device movable relative to the first, and another gathering device carried by the second and movable therewith.

56. In a machine of the class described, a frame, a gathering device fixed thereto, a second gathering device movable relative to the first, and another gathering device suspended 50 from the second and movable therewith.

57. In a machine of the class described, a frame, a gathering device fixed thereto, a second gathering device movable relative to the first, another gathering device carried by the second and movable therewith, and means for driving said last two gathering devices in conjunction.

58. Gathering mechanism for a machine of the class described comprising driving means, a movable gathering device actuated thereby, a second gathering device rigidly suspended from said first named gathering device and laterally offset therefrom, and a drive connec-

tion between said first named gathering device and said second gathering device.

59. Gathering mechanism for a machine of the class described comprising driving means, a pivotally mounted gathering device actuated thereby, a second gathering device rigidly suspended from said first named gathering device and laterally offset therefrom, and a drive connection between said first named gathering device and said second gathering device.

60. Gathering mechanism for a machine of the class described comprising a drive shaft, a gathering device pivoted on said shaft and driven thereby, and having its major portion laterally offset therefrom, a second gathering device carried by said first named gathering device, and a drive connection between said first named gathering device and said second device.

61. Gathering mechanism for a machine of the class described comprising a drive shaft, a gathering device having a laterally bent end pivoted to said shaft, a driving connection between said shaft and said gathering device, a second gathering device carried by said first named gathering device, and a driving connection between the other end of said first named gathering device and said second gathering device.

62. In a machine of the class described, a frame, a gathering device fixed thereto, a second gathering device movable relative thereto, another gathering device suspended from the second and movable therewith, and means for driving said last two gathering devices in conjunction.

63. In a machine of the class described, the combination of conveying mechanism comprising a supporting pan, a vertical shaft mounted at the forward end of said pan, means for driving said shaft, a cutting and gathering device rigidly mounted with respect to and driven by said shaft, a second cutting and gathering device pivotally mounted with respect to and driven by said shaft, and means for intermitting the driving action of said shaft on said second cutting and gathering device.

64. In a machine of the class described, the combination of conveying mechanism comprising a supporting pan, a vertical shaft mounted at the forward end of said pan, means for driving said shaft, a cutting and gathering device rigidly mounted with respect to and driven by said shaft, a second cutting and gathering device pivotally mounted with respect to and driven by said shaft, means for intermitting the driving action of said shaft on said second cutting and gathering device, and means for locking said movable cutting and gathering device in active and inactive positions.

65. In a machine of the class described, the combination of conveying mechanism com-

prising a supporting pan, a vertical shaft mounted at the forward end of said pan, means for driving said shaft, a cutting and gathering device rigidly mounted with respect to and driven by said shaft, a second cutting and gathering device pivotally mounted with respect to and driven by said shaft, means for intermitting the driving action of said shaft on said second cutting and gathering device, means for locking said movable cutting and gathering device in active and inactive position, and means for preventing operation of said locking device when said movable gathering device is in its inactive position.

66. In a coal mining machine, the combination of a conveyer, a main elongated cutter arm projecting horizontally in fixed relation to said conveyer, an endless cutter chain on said arm adapted to cut a path therefor in a coal face and to move loose material toward said conveyor when the conveyor and cutter arm are moved to advance the latter laterally, an auxiliary cutter arm movable with the main cutter arm and in the same direction, said auxiliary cutter arm having a cutter chain adapted to cooperate with the chain of the main cutter arm in moving loose material toward the conveyor, said auxiliary cutter arm being inactive during the cutting movement of said main cutter arm, the direction of movement of said main cutter arm being the same in both the cutting and gathering operations, and means to bodily move the conveyor and cutter arms to perform the described operations.

67. In a coal mining machine, the combination of a conveyor, a main elongated cutter arm projecting horizontally in fixed relation to said conveyor, an endless cutter chain on said arm adapted to cut a path therefor in a coal face and to move loose material toward said conveyor when the conveyor and cutter arm are moved to advance the latter laterally, an auxiliary cutter arm movable with the main cutter arm and in the same direction, said auxiliary cutter arm having a cutter chain adapted to cooperate with the chain of the main cutter arm in moving loose material toward the conveyor, said auxiliary cutter arm being inactive during the cutting movement of said main cutter arm, the direction of movement of said main cutter arm being the same in both the cutting and gathering operations, and means to bodily move the conveyor and cutter arms in a rectilinear path to perform the described operations.

68. In a machine of the class described, a cutting mechanism bodily movable to form a kerf in a coal face adjacent the mine floor and also to drag out loose material, and gathering mechanism bodily adjustable into position to cooperate with said cutting mechanism in another plane in the dragging out operation.

69. In a machine of the class described, a frame, cutting mechanism carried by said frame in fixed relation thereto, means to move said frame and therewith said cutting mechanism to form a kerf in a coal face adjacent the mine floor or to drag out loose material, and gathering mechanism carried by said frame and bodily adjustable into position to cooperate with said cutting mechanism in another plane in the dragging out operation.

70. In a machine of the class described, a cutting mechanism bodily movable to form a kerf in a coal face and also to drag out loose material, and gathering mechanism swingable into substantially parallel superposed relation to said cutting mechanism to cooperate with the latter in dragging out the loose material to a common point of delivery.

71. In a machine of the class described, a cutting mechanism bodily movable to form a kerf in a coal face and also to drag out loose material, gathering mechanism swingable into superposed relation to said cutting mechanism about a pivot point directly above the latter to cooperate with the latter in dragging out the loose material to a common point of delivery, and means to lock said gathering mechanism in such cooperating position.

72. In a machine of the class described, a cutting mechanism bodily movable to form a kerf in a coal face at the mine floor and also to drag out loose material, and gathering mechanism swingable into superposed relation to said cutting mechanism to cooperate with the latter in dragging out the loose material to a common point of delivery, and disengageable driving connections for said gathering mechanism.

73. In a machine of the class described, a frame, elongated cutting mechanism projecting from said frame in fixed relation thereto, means to move said frame and therewith said cutting mechanism to engage a lateral edge of the latter in a coal face to form a kerf therein or to engage said edge with a mass of loose material to drag it out, and a gathering mechanism pivoted to said frame and swingable into superposed relation to said cutting mechanism to cooperate with the latter at the same side of the frame in dragging out the loose material to a common point of delivery.

74. In a machine of the class described, a frame, elongated cutting mechanism projecting from said frame in fixed relation thereto, means to move said frame and therewith said cutting mechanism to engage the lateral edge of the latter in a coal face to form a kerf therein or to engage said edge with a mass of loose material to drag it out, a gathering mechanism pivoted to said frame and swingable into superposed relation to said cutting mechanism to cooperate with the latter at the same side of the frame in dragging out the loose material to a common point of delivery,

and means to lock said gathering mechanism in such cooperating position.

75. In a machine of the class described, a frame, elongated cutting mechanism projecting from said frame in fixed relation thereto, means to move said frame and therewith said cutting mechanism to engage a lateral edge of the latter in a coal face to form a rectilinear kerf therein or to engage said edge with a mass of loose material to drag it out, and gathering mechanism carried by said frame and bodily adjustable into position to cooperate with said cutting mechanism in another plane at the same side of the frame in dragging out the loose material to a point of delivery.

In testimony whereof I have hereunto set my hand.

NILS D. LEVIN.
